Fig. 1.

Fig. 2.

Fig. 3.

Fig. 4.

FIG. 1 is a perspective view taken from the front, top and one end of the ventilating range hood embodying my new design.

FIG. 2 is also a perspective view and taken from the front, bottom and other end of the hood.

FIGS. 3 and 4 are fragmentary sectional views taken as indicated by lines 3—3 and 4—4 on FIG. 1, and illustrate the detailed characteristics of the hood.

The essential features of my design reside in the portions shown in full lines. The horizontal broken lines and the stippling on the face of the panel are intended to show contrast.

I claim:

The ornamental design for a ventilating range hood, as shown and described.
